UNITED STATES PATENT OFFICE.

ETHEL L. PATTEE, OF ARLINGTON, MASSACHUSETTS.

DESIGN FOR A CHILD'S APRON.

54,767.

Specification for Design.

Patented Mar. 23, 1920.

Application filed January 23, 1918. Serial No. 213,419. Term of patent 7 years.

To all whom it may concern:

Be it known that I, ETHEL L. PATTEE, a citizen of the United States, and a resident of Arlington, Middlesex county, State of Massachusetts, have invented a new, original, and ornamental Design for a Child's Apron, of which the following is a specification, reference being had to the accompanying drawing, in which—

Figure 1 is a front view of a child's apron, embodying my new design, and Fig. 2 is a rear view thereof.

The colored ornamentations indicated by way of example in the drawing by the shading, may be varied, without departing

from my invention, the essence of which resides in the general appearance of the child's apron, substantially as shown and described.

It is to be understood, that my claim includes all substantial equivalents of my design, as shown and described.

I claim:

The ornamental design for a child's apron, substantially as shown and described.

In testimony whereof I have hereunto set my hand.

ETHEL L. PATTEE.
